CHECK OPENING GUARD AND CHECK

Benjamin D. Weller, Cleveland Heights,
Ohio

Application January 9, 1933, Serial No. 650,766

6 Claims. (Cl. 194—4)

This invention relates to improvements in check controlled apparatus, and the invention refers more specifically to a novel guard for obstructing the passage of an unauthorized check or "slug" through the check receiving opening of the apparatus, and to the combination with such a guard of a peculiar form of check adapted for use therewith.

While the invention is adapted for use generally in connection with other types and forms of check-controlled apparatus, it is particularly adapted for use in connection with pay telephones and more specifically with that type of pay telephone having a coin box with coin-receiving openings in which the coins are adapted to be inserted flatwise. At the coin-receiving portion of such boxes, the walls are usually so closely spaced that, as a practical consideration, it is virtually impossible to insert a coin edge-wise into the opening. Moreover, as a general rule, the coin-receiving openings thereof are devoid of any obstructions or guard means, so that it is a relatively simple matter to deposit in the boxes unauthorized circular metallic, and even non-metallic slugs. While certain types of vending machines have been provided with magnetic or electro-magnetic detecting devices, the use of which is effective to prevent the insertion of slugs of unauthorized metal or size or non-metallic slugs in the slots of such machines, the speed with which the coin drops in the coin boxes of pay telephones renders impractical the use of such magnetic or electro-magnetic devices in telephone boxes. The unauthorized slugs, as a general rule, are in the form of circular steel discs, annular steel washers, brass checks, steel-bound paper tags, etc., which have lawful uses and the mere possession of which is not a criminal offense. In the event that a person is detected in the act of using or attempting to use such slugs, it is a very difficult matter to prove criminal intent, and indictments based on such acts are therefore very rare. Even where indictments are proved, the punishment is usually very light.

In certain localities, the coin boxes are provided with guard means which renders it necessary to purchase a check of special shape to deposit in the openings thereof. In one instance, an arm having a pear-shaped extremity extends radially into the opening, making it necessary to purchase a check having a radial slot terminating in a central pear-shaped opening for insertion into such opening. Such checks are objectionable because they can be easily duplicated by simple mutilation of the usual types of slugs which have been described, and it is in fact possible to use semi-circular slugs, or slugs cut from an H-bar and having the flanges curved or bent into semi-circular shape, and either of which

may be inserted through the opening without striking the aforesaid arm.

It is a primary object of the present invention to provide novel guard means for obstructing the passage of unauthorized checks or slugs such as those which have been described through the check-receiving openings of check-controlled apparatus, particularly pay telephones, but which shall be effective to permit the passage of authorized checks which are sold for specific use in such apparatus. Another object of the invention is to provide a check especially adapted for use in check-controlled apparatus, particularly pay telephones, which shall be of somewhat intricate contour so as to render duplication thereof by mutilation of existing types of slugs extremely difficult, which shall be difficult to counterfeit except with expensive dies or casting equipment and the character of which, on account of its peculiar design, may be easily recognized, so as to render it difficult for a person to explain away an attempt to use the counterfeit check. To the accomplishment of the foregoing and related ends, said invention, then, consists of the means hereinafter fully described and particularly pointed out in the claims.

The annexed drawing and the following description set forth in detail certain structure embodying the invention, such disclosed means constituting, however, but one of various structural forms in which the principle of the invention may be used.

In said annexed drawing:

Fig. 1 is a fragmentary front elevation of a coin box of a pay telephone, showing the coin-receiving openings, therefor; Fig. 2 is a cross-sectional view, taken on a plane substantially indicated by the line 2—2 of Fig. 1; and Fig. 3 is a perspective view of the check of the present invention.

Referring more particularly to the drawing, it will be seen that the telephone box 1 is provided with openings 2, 3, and 4, which correspond to the usual openings for the reception of nickels, dimes and quarters, respectively.

For the purpose of preventing the insertion of unauthorized slugs in said openings, each opening is provided with guard means consisting of a pointed arm 5 which extends radially into the opening and preferably beyond the center thereof, and a second arm 6 which also extends radially into the opening from a point on the periphery of the opening substantially diametrically opposite to the point from which the arm 5 extends, and which is provided with diverging branches 7 having blunt ends. In addition to these members, the openings are provided with auxiliary pointed members 8, which also extend radially thereinto from points spaced approximately 120° from the arm 5. It will be particularly noted that the arm 6 is in alignment with the arm 5 and that the

branches 7 terminate at a line $x-x$, which intersects the arm 5. Any plane at right angles to the plane of the opening and passing diametrically across the opening necessarily intersects one or more of the members 5, 6, 7 and 8. This makes it virtually impossible to enter a slug of the diameter or substantially the diameter of the opening edgewise therethrough. The obstruction imposed by the branches 7 makes it virtually impossible to insert a semi-circular slug of substantially the diameter of the opening flatwise into the opening.

It will be also noted as indicated by the circle A in Fig. 1, that the members 8 extend at least as far radially inwardly as the distance between the periphery of the opening and points on the branches 7 most closely adjacent to the periphery. This makes it virtually impossible to utilize any of the well-known types of slugs for flatwise insertion into the openings 2, 3 and 4. Annular steel washers could not be made to pass the members 8, and even if such washers were filed to pass these obstructions, they could not, without splitting them in half, be made to pass both the arms 5 and 6. The flatwise insertion of an H-bar slug would be prevented not only by the presence of the members 8, but also by the fact that the horizontal cross-member of such slug could not be made to pass between the extremities of the arm 5 and branches 7 without bending such cross-member.

It will be further noted that the obstructing members 5, 6, 7 and 8 are fixed and are so arranged within the opening that a straight line drawn between any two points on the wall about the opening spaced by a central angle greater than about 120° will intersect at least one of the obstructing members. Three such lines are indicated by the reference characters B, C, and D, in Fig. 1. With this arrangement of the obstructing members, the insertion of any slug which is of a diameter greater than the length of the aforesaid line is effectively prevented.

A check which is to be used for the specific purpose of insertion into the openings 2, 3 and 4, must therefore necessarily assume a form, such as shown by way of example in Fig. 3. This check consists of a disk-like metallic member having a slot 9 extending radially inwardly from one point in the periphery thereof, a slot 10 extending radially inwardly from a point in the periphery substantially diametrically opposite the point from which the slot 9 extends and having diverging slots 11 extending therefrom and notches or recesses 12 at intermediate points in the periphery of the member, preferably at points 120° from the points from which the slots 9 extend. The various portions of the check are of such dimensions as to permit the check to be easily inserted in the openings of the coin box, but without excessive clearance between the portions thereof and the corresponding guard portions of the openings.

It will be apparent that the contour of the check is such as to render duplication thereof by mutilation of existing types of slugs extremely difficult and therefore undesirable, and that counterfeiting of the checks, which would require expensive dies or casting equipment, would be impractical, because of the difficulty of successfully explaining away the possession or attempted use of the counterfeit checks.

While I have shown and described the invention as particularly adapted for use in connection with the coin boxes of pay telephones, it is to be understood that the invention is also adapted to be used

in connection with other types of check-controlled apparatus as well as vending machines of various types.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a check-controlled apparatus having a check receiving opening, means for preventing the insertion of unauthorized slugs in said opening, said means including an arm extending radially into said opening from a point on the periphery thereof, and a Y-shaped member extending into said opening from a point on the periphery substantially diametrically opposite said arm, the branches of said Y terminating in a line intersecting said arm.

2. In a check-controlled apparatus having a check receiving opening, means for preventing the insertion of an annular washer in said opening including a Y-shaped member extending into said opening from a point on the periphery and auxiliary members extending from other points on the periphery and inwardly at least as far as the distance between the periphery and the extremities of the branches of said Y.

3. In a check controlled apparatus having a check receiving opening, means for preventing the insertion of unauthorized slugs in said opening, said means including an arm extending radially into said opening from a point on the periphery thereof, a Y-shaped member extending into said opening from a point on the periphery substantially diametrically opposite said arm, and auxiliary members extending from other points on the periphery and inwardly at least as far as the distance between the periphery and the extremities of the branches of said Y.

4. In a check-controlled apparatus having a check-receiving opening, means for preventing the insertion of unauthorized slugs in said opening, said means including an arm extending radially into said opening from a point on the periphery thereof, a Y-shaped member extending into said opening from a point on the periphery substantially diametrically opposite said arm, and auxiliary members extending from other points on the periphery and inwardly at least as far as the distance between the periphery and the extremities of the branches of said Y, the branches of said Y terminating in a line intersecting said arm.

5. A check for use in check-controlled apparatus comprising a circular member having a slot extending radially thereinto from a point in the periphery thereof and a Y-shaped slot extending into said member from a point on the periphery diametrically opposite the first-named slot, the branches of said Y terminating in a line intersecting the first-named slot.

6. A check for use in check-controlled apparatus comprising a circular member having a Y-shaped slot extending into said member from a point on the periphery thereof and other recesses extending into said member from the periphery thereof and to a point at least as far as the distance between the periphery and the extremities of the branches of said Y slot.
